(57) **CLAIM**

The ornamental design for an ignition gun as shown and described.

DESCRIPTION

FIG. 1 is a front view of an ignition gun, showing our new design;

FIG. 2 is a rear view of the ignition gun of FIG. 1;

FIG. 3 is a left-side view of the ignition gun of FIG. 1;

FIG. 4 is a right-side of the ignition gun of FIG. 1;

FIG. 5 is a top view of the ignition gun of FIG. 1;

FIG. 6 is a bottom view of the ignition gun of FIG. 1;

FIG. 7 is a perspective view of the ignition gun of FIG. 1;

FIG. 8 is an enlarged top view of the ignition gun of FIG. 1; and,

FIG. 9 is an enlarged bottom view of the ignition gun of FIG. 1.

The broken lines in the drawings depict environmental structure of an ignition gun that form no part of the claimed design.
